COMBINED HOOD AND GRILLE FOR A TRACTOR AND THE LIKE

Henry Dreyfuss, South Pasadena, William F. H. Purcell, Pasadena, and James M. Conner, Glendale, Calif.,
assignors to Deere & Company, Moline, Ill., a corporation of Delaware

Filed Nov. 9, 1960, Ser. No. 63,093

Term of patent 14 years

(Cl. D14—3)

FIG. 1

FIG. 2

FIG. 3

FIG. 4

FIG. 5

FIG. 6

FIG. 1 is a side elevational view of a combined hood and grille for a tractor and the like showing our new design.

FIG. 2 is a top plan view thereof.

FIG. 3 is a side elevation as seen from the right side.

FIG. 4 is a perspective view as seen from the right front thereof.

FIG. 5 is a perspective view as seen from the left front thereof.

FIG. 6 is a perspective view as seen from the top and front thereof.

We claim:

The ornamental design for a combined hood and grille for a tractor and the like, substantially as shown.
